[57] CLAIM

The ornamental design for a golf putter head, substantially
as shown.

DESCRIPTION

FIG. 1 is a top plan view of a golf putter head showing my
new design therefor;

FIG. 2 is a side elevational view thereof, the undisclosed
side being the same;

FIG. 3 is a front elevational view thereof;

FIG. 4 is a rear elevational view thereof; and,

FIG. 5 is a bottom plan view thereof.

The broken line showing of a fragmented shaft is for
illustrative purposes only and forms no part of the claimed
design.
